[57] CLAIM

The ornamental design for a slip-on cover for a fishing lure, as shown and described.

DESCRIPTION

FIG. 1 is a perspective view of a slip-on cover for a fishing lure in operative position on a plug;

FIG. 2 is a top plan view thereof;

FIG. 3 is a right end view thereof;

FIG. 4 is a left end view thereof;

FIG. 5 is a bottom plan view thereof;

FIG. 6 is a front side elevational view thereof; and,

FIG. 7 is a rear side elevational view thereof.

The broken-line portions of FIG. 1 are for purposes of illustration only and form no part of the instant design.

FIG. 1

FIG. 2

FIG. 3

FIG. 4

FIG. 5

FIG. 6

FIG. 7
